INSERTION OF FASTENINGS

Frank E. Stratton, Beverly, Mass., assignor to
United Shoe Machinery Corporation, Flemington, N. J., a corporation of New Jersey

Application October 2, 1941, Serial No. 413,329

62 Claims. (Cl. 12—42)

This invention relates to the insertion of fastenings for securing together work-pieces, it being particularly adapted for the attachment of heels to shoes.

One of the well known methods of attaching shoe-heels is by a screw inserted through the heel-seat and into the heel, this screw becoming a part of the completed shoe. In carrying out this procedure, it is customary, after clamping the heel in place upon the shoe, to drill through the heel-seat into the heel, and then to turn by a screw-driver a screw into the hole thus formed, said screw-driver being rotated through a friction or other device, which will yield upon encountering the resistance produced by the completion of the insertion and the sinking of the screw-head into the insole. The rate of rotation is indeterminate; and the extent and degree of the advancing pressure applied to the screw-driver is dependent upon the judgment of the operator. Such a method is time-consuming; the depth to which the screw will be inserted is uncertain; excessive rotation may tear out the thread which the screw forms in the heel; and the difference between the rate of advance of the screw-driver and the natural rate of the screw under the influence of its thread may set up forces tending to rupture the screw, both by torsion and tension. An object of my invention is to reduce the time and effort required for the insertion of a fastening, and to effect such insertion without danger of injury to the work.

In the attainment of the above object, I combine with a work-support and co-operating screw-driver of a fastening-inserting machine, means for both rotating the screw-driver and for advancing it at a rate corresponding to the pitch of the attaching screw to be inserted in the supported work. When the movements of the screw-driver and screw thus coincide, the screw may be caused to enter and seat itself in the work without destructive stresses being set up, either in the elements secured or in the screw. By advancing the screw-driver through a predetermined distance, screws of all lengths may be inserted with their heads properly disposed as to the surfaces which they enter. The correct relation between screw-rotation and advance may be obtained by employing gearing for effecting such rotation and a cam for producing the advance. The rotation of the screw-driver may be stopped to allow the bit to seat itself in the slot of the screw-head, after which it is resumed for the full insertion of the screw. There may thus be prevented the tearing and chipping of the screw-head. This

action is permitted by rotating the screw-driver through clutch-sections, preferably of the friction-type, normally separated by an interposed spring and brought into engagement under the screw-advancing force. I have shown the shoe-support as in the form of a tube, adapted to receive a passage in the cone of a last within the shoe, in which tube is a screw-supporting or -engaging tube, a screw-driver being movable in the tubes. The second of the tubes is movable within the first, it holding the longitudinal axis of the screw symmetrical with that of the outer tube, as it carries the point into engagement with the work and then remaining at rest, while a spring through which it is actuated is compressed, the screw-driver advancing through the tubes to insert the screw. Both the rotation and advance of the screw-driver are produced by the previously mentioned clutch-sections, the driven section being connected to the screw-driver and also acting upon the screw-engaging tube. The driving section of the clutch is preferably rotatable upon a plunger engaged by the cam which causes the advance of the screw-driver. A spring interposed between the screw-engaging tube and a relatively fixed point holds said tube yieldably in its normal retracted position, while a spring between the tube and the driven clutch-section allows relative movement between the tube and screw-driver. The screw-engaging tube is not only elevated under the power of the machine to advance the screw into preliminary engagement with the work, but may also be elevated by the operator, permitting inspection and the removal of chips which may be resting upon the end of the tube and which would disturb the alignment of the screw.

In the machine, there are further combined novel means for dividing the resistance of the work to displacement under the influence of clamping pressure between two supports, one of which is movable by the work and which is locked when the supporting effect is properly divided; treadle mechanism for applying the clamping pressure and which reduces the effort required by the operator; convenient means whereby the power-cycle of the machine is controlled from the treadle mechanism; pressure means for the work movable into and out of operating position to facilitate the application of said work to its support; and clutch mechanism by which the pressure means is locked in clamping relation to prevent transmission of the reaction back to the treadle mechanism and to the operator's foot.

55 In the accompanying drawings,

Fig. 1 shows the upper portion of one embodiment of my improved machine in broken front elevation;

Fig. 2 is a broken side elevation of the same portion of the machine;

Fig. 9, a sectional detail of the locking screw and its more closely associated parts; and

Fig. 10, an enlarged broken side elevation of the work and directly co-operating elements at the completion of insertion of a heel-attaching screw.

An enclosed base 10 has secured to its top a support 12, upon which the column 14 is mounted. In the top of this column is threaded an adjusting nut 16, which may be latched in position by a spring-detent 18 entering some one of a series of vertical notches about the nut (Fig. 2). Seated upon the upper extremity of the nut, and extending above and down into the column 14, is the flange 20 of a sleeve or tube 22 (Fig. 1). This tube is arranged to serve as a work-supporting spindle, it being adapted to enter a passage through the cone of a last contained in a shoe, the heel of which is to be attached. Movable within the tube 22 is a sleeve or tube 24, the lower extremity of which has a tubular enlargement 26. Upon the upper face of the enlargement rests a ball-bearing 28, supporting a compression-spring 30 surrounding the tube 24 and engaging at its upper extremity a washer 32, which contacts with a surface upon the interior of the nut 16. Below the enlargement 26 of the tube 24 is a collar 34, surrounding the head 36 of a screw-driver 38. The shank of this screw-driver extends up within the tube 24, with some clearance, while the bit 40 lies at the level of, or just below, the upper extremity of the tube, and is formed upon an enlargement 42 fitting said tube for rotation therein. The collar 34 is carried upon a compression-spring 44 which surrounds it and rests at its lower end upon the upper section 46 of a friction-clutch, through which the screw-driver is rotated. The screw-driver-head 36 is threaded into the hub of this clutch-section, which is surrounded by the collar 34. In the collar is a vertical slot, and passing through the hub of the clutch-section 46 is a pin 48 against which the bottom of the slot is normally held by the spring 44. The clutch-section 46 is carried upon a pin 50 normally elevated by a compression-spring 52. This spring lies within a bore in a pinion 54 having vertically elongated teeth. Secured to the upper end of the pinion is the lower section 56 of the clutch for the screw-driver. Meshing with the pinion 54 is a gear 58 upon the upper extremity of a vertical counter-shaft 60. This shaft is rotated through bevel-gearing 62 from a shaft 64 turning horizontally in the support 12 and actuated constantly during the operation of the machine through a pulley 66. These connections rotate the screw-driver 38 upon engagement of the clutch-sections 46 and 56. Upon

the lower portion of the shaft 60 is a worm 68 meshing with a worm-wheel 70 upon a shaft 72 journaled horizontally in the support. The last-mentioned shaft carries a cam 74, upon which

5 rests a plunger 76 guided for vertical movement in the support, and upon the upper extremity of which the pinion 54 is rotatable. The worm-wheel is free to turn about the shaft 72, but may be compelled to rotate with said shaft by a 10 single-rotation clutch C, controlled as will hereinafter appear.

The inserting operation of the screw-driver takes place in the following manner. The operator, first dropping a screw s, head down, into the 15 tube 22 upon the end of the tube 24, applies the passage through the cone of a last L within a shoe S to be heeled to the tube 22. The last-plate has an opening of less diameter than the outside diameter of the tube 22, it furnishing at 20 l a shoulder overhanging the passage and contacting with the upper extremity of the said tube. The initial distance between the tube-ends will at least equal the length of the longest screw to be used. Then a heel H is positioned upon 25 the heel-seat of the shoe, and, by treadle mechanism T, illustrated in Figs. 3 and 4, the operator brings down upon the work a pressure-head or work-holdown P. The treadle mechanism and pressure-head will later be described in detail. When the clutch C is tripped, the cam 74 starts its rotation and raises the plunger 76 with the pinion 54 and lower clutch-section 56. Through the spring 52, pin 50 and clutch-section 46, the screw-driver 38 is lifted and, by way of 30 the section 46, the spring 44 and the collar 34, the inner tube 24 is similarly elevated. This continues until the point of the screw engages the insole of the shoe. As movement of the screw and tube 24 is resisted, the spring 30 yields; the 35 screw-driver continues to rise, the spring 44 compressing, and will come into contact with the head of the screw, forcing the point into the heel-seat of the shoe. The relative longitudinal movement between the screw-driver and the tube 40 24 will be permitted by the travel of the pin 48 in the slot in the collar 34. At this time, the combined resistance of the springs 30 and 44 will cause the spring 52 to be compressed, and the sections 56 and 46 of the clutch will come into 45 driving engagement, turning the screw-driver to find the slot in the screw-head. As the screw-driver-bit comes into registration with the slot, it is forced into said slot by the expansion of the spring 52. This allows the clutch-section 46 to 50 separate automatically from the companion section, so rotation of the screw-driver momentarily stops, giving the bit an opportunity to fully seat itself. Then the continued rotation of the cam 74 effects the re-engagement of the clutch-sections 55 to again turn the screw-driver to insert the screw through the heel-seat into the heel. The relation between the predetermined rate of elevation of the screw-driver by the cam 74 and its rotation by the gearing 54, 58, produces a movement which corresponds to the pitch of the screw being inserted. Consequently, this is driven into the work without tearing out the thread, which itself produces in the wood of the heel, and with 55 relatively little resistance. As the head of the screw contacts with the resistive material of the heel-seat, it tends to be held back, while the portion in the heel continues its advance at a rate determined by the pitch of the thread. Before there can be applied a dangerous longitudinal strain resulting from the delayed travel of the 60 65 70 75

head, the clutch-sections slip. This is followed immediately by the application of such a force by the cam that the resistance to the head is overcome, and the insertion is completed with the same advancing forces for all portions of the screw, rupturing stresses thus being avoided. The head of the screw will be driven always into a definite relation to the insole, as flush with its inner surface, because the travel of the bit 40 of the screw-driver, as produced by the cam, is unvarying. The depth of insertion of the screw-head may be varied by raising and lowering the outer tube 22, this being effected by rotation of the nut 16 and altering the initial distance between the screw-driver-bit and the end of the tube. The head of the screw, resting upon the inner tube 24 within the outer tube, is held against angular displacement, its axis being maintained in alinement with that of the screw-driver and entering the work in the proper direction. When the cam 74, at the end of its rotation upon the opening of the clutch C, releases the plunger 76, the springs 30, 44 and 52 return the elements to normal.

In the use of the machine, fragments of leather or metal chips from the screw-heads may fall into the tube 22 and rest upon the end of the inner tube 24 and the bit of the screw-driver. These, engaged by the heads of the introduced screws, would so tilt said screws that they would not enter the work in proper alinement with the screw-driver. I facilitate the removal of obstructions of this character by the provision of means for raising the inner sleeve and the screw-driver manually. Formed upon the front of the plunger 76 is a vertical series of rack-teeth 80, with which meshes a pinion 82 fast upon a shaft 84, journaled across the front of the support 12 and to one extremity of which a hand-lever 86 is secured. At any time, the operator may turn down the hand-lever to lift the ends of the tube 22 and the screw-driver to the top of the tube 22 for examination and the removal of chips.

If the work is supported wholly by the engagement of the last-plate-shoulder 1 with the end of the spindle or tube 22, the clamping pressure applied by the head P may deform said last-plate. To avoid this, I distribute the pressure between the last-plate and the crown of the last-cone, an auxiliary work-support being provided for the latter. Fulcrumed at 87 upon the frame is a horizontal lever 88 (Fig. 2). This carries in a socket at its forward extremity a universally tiltable supporting member or bed-piece 90 for the crown of the last-cone. Rotatable upon the lever between its fulcrum and the last-bed-piece is a roll 91, resting upon the upper end of a threaded spindle 92 (Fig. 9), which passes through a nut 94 rotatable in a mounting 96 carried upon the top of the support 12. The nut may be locked temporarily against rotation by a double detent 98, 98 (Fig. 8) pivoted adjacent to it and urged toward teeth 100 upon the periphery of the nut by scissors-springs 102, 102 secured to a horizontal stem 104 projecting from the core 106 of a solenoid 108. An eccentric stop 110 adjustably limits the extent of outward movement of the detents. These detents are normally held away from the nut-teeth by a retaining loop 112, projecting from the end of the stem 104 through a guide 113 carried by said stem, the loop passing vertically at its outer end through openings in the detents. The stem is engaged by the end of a torsion-spring 114 attached to the mounting 96, and which yieldably holds the loop

and detents, together with the core 106, as far to the left as is permitted by the stop 110. The detents are thus normally out of engagement with the teeth 100. The winding of the solenoid 5 108 is in circuit with a switch 109 (Fig. 2), which may be closed upon engagement of the pressure-head P with the work, as hereinafter described. The spindle 92 is elevated, and with it the lever 88 and the last-bed-piece 90 to an extent permitted 10 by a stop-screw 116 threaded through the lever, by an expansion-spring 118 which surrounds said spindle between the mounting 96 and a collar 120 adjustable upon the spindle. In this movement, the thread upon the spindle travels through the 15 nut, this turning idly. The normal position of the bed-piece 90 is such that last-cones of all heights will produce some depression when pressure is applied to the work. Consequently, the crown of the last-cone will always have a bearing 20 upon the bed-piece. When the pressure-head P causes the closing of the switch 109, the solenoid 108 is energized. This shifts the core 106 and its stem 104 to the right (Fig. 8), carrying the retaining loop 112 away from the detents 98, so 25 the springs 102 force them into engagement with the teeth 100 upon the nut 94. The nut is thereby locked against rotation, and prevents any further downward movement of the spindle 92. The work is now supported upon the bed-piece 90 30 as well as upon the end of the tube 22, so the pressure will be distributed between the two elements. As a result of this, the shoulder 1 of the last-plate will not be deformed by pressure upon the tube-end. If the shoulder were omitted and 35 the insole of the shoe allowed to engage the tube-end, indentation of the insole would be avoided by this distribution of pressure.

Considering now the clamping of the work for the operation upon it, there is guided at the opposite sides of the frame vertical side-rods 122, 122 (Fig. 1). These are connected at their upper extremities to a top-girt 124 carrying the pressure-head P and below by a cross-girt 126 (Fig. 4). Fulcrumed at 128 within the base 10 40 is a treadle-lever 130 of the mechanism T with its foot-pad 132 held normally raised by a tension-spring 134 extending between the top of the base and the treadle in front of the fulcrum and 45 by a weight 136 hung upon arms 138, projecting rearwardly from the fulcrum-rod, and steadied by a link 140 pivoted to the weight and to the base. Fulcrumed at 142 upon the treadle-lever is a lever 144, a projection 145 from which rests 50 normally against a cross-rod 146 upon the treadle. The forward end of the lever 144 is joined by a link 147 to a lever 148, fulcrumed at 149 at the front of the base and connected by spaced links 150, 150 to the underside of the cross-girt 126. Fulcrumed at 142 with the lever 55 144 is a second lever 152, which, at its outer extremity, is held yieldably against the end of the lever 144 by a tension-spring 154 extending between them. The levers 144 and 152, which may be considered as clutch-levers, are bowed outwardly to receive the spring. At the rear of the 60 fulcrum, the lever 152 has rotatable upon it a roll 156 for actuating clutch mechanism c. This mechanism has a normally stationary block 158 pivoted upon the treadle-lever at 160 and adjustable as to its angle by a screw 162, threaded through a portion of the treadle-lever and against which it is held by a tension-spring 164. Guided upon the stationary block 158 is a movable clutch-block 166 for engagement by the roll 156. Between the blocks 158 and 156 passes a clutch-rod 65 70 75

168, which is joined by a sectional link 170 to the rear extremity of the lever 148. The link 170 has between its sections a loaded compression-spring 172. The clutch-rod is guided by a rod 174 extending upwardly from the treadle-lever and having about it an arm 176 projecting from a head of the link 170.

To create engagement of the pressure-head P with the work, the operator fully lowers the treadle by pressure of his foot upon the pad 132. The lever 144 transmits the motion through the link 147, lever 148, links 150, cross-girt 126, side-rods 122 and top-girt 124 to the pressure-head, lowering this for the application of preliminary pressure. Because the connection of the lower end of the link 147 to the treadle is, in effect, close to the foot-pad, and that of the upper end of the link in proximity to the cross-girt, this movement is rapid, being substantially that of the operator's foot. When the travel of the pressure-head is arrested by its contact with the work, the movement of the lever 148 will be stopped. The link 147 holds stationary the forward end of the lever 144, but movement of the treadle continues. This will lower the fulcrum 142 and carry the forward end of the lever 152 away from that of the lever 144, the spring 154 yielding. The contraclockwise swing of the lever-fulcrum 142 (Fig. 4) causes the roll 156 and the block 166 to be brought into engagement with a force limited by the spring. This clutches the rod 168 to the treadle-lever, so the final movement of the foot-pad 132 is transmitted through the link 170, spring 172 and lever 148, and then, as for the preliminary pressure, to the head P. Because of the ratio between the lever-arms formed between the lever-fulcrum 128 and the rod 168 and between said fulcrum and foot-pad 132, and, further, because of a similar ratio between the lever-fulcrum 148 and the connection of the links 150 and between this fulcrum and the link 170, the force applied by the operator will be twice multiplied. With this final clamping pressure, little effort is required to hold the work firmly in place upon the tube 22 and bed-piece 90, to resist the displacing effect produced by the insertion of a screw. However, on account of the interposition of the loaded spring 172, the hold-down-pressure will be limited to that which will compress said spring, and crushing of the heel may thus be avoided.

The pressure-head P has a slide 180 (Fig. 2) movable upon the top-girt in horizontal ways 181 (Fig. 1) forwardly and rearwardly, the former position being determined by a stop-screw 182 threaded through the front of the head. The heel-engaging members consist of the usual tread-abutment 184 and rear abutment or fork 186, the tread-engaging surface being adjustable as to angle by a screw 188, while the angle of the fork may be varied by a screw 190. Depending from the rear of the top-girt are arms 192, 192 between which is fulcrumed a bell-crank-lever having three arms 194, 196 and 198. The arm 194 is joined to the slide 180 by a link 200. To the arm 196 a tension-spring 202 is connected, the opposite end being attached to the top-girt and serving to draw the slide forward. Through the third arm 198 a rod 204 passes, this at its lower end being attached at 206 to the top of the base 18. Above the last-mentioned arm, a collar 208 is fixed to the rod. When the top-girt is elevated in its normal position, which may be effected by the spring 134 and the weight 136 acting upon the treadle-lever 130, the arm 198

of the bell-crank-lever comes into contact with the collar. This draws the slide 180 back against the tension of the spring 202, and leaves the tube 22 clear for the application of the work.

5 When the operator treads and draws down the top-girt 124, the lever-arm 198 travels away from the collar. The tread and rear abutment members of the head, under the influence of the spring 202, approach in an inclined direction the heel 10 which has been applied to the heel-seat of the lasted shoe upon the sleeve, and settle into engagement with it.

The action of the tread-abutment 184 and the rear fork 186, occurring when they first contact 15 with the heel, is utilized to effect the closure of the switch 109, thus locking the nut 94 of the last-supporting lever 88 against rotation. When the pressure-head P is lowered, the tread-abutment and fork engage the work, the intermediate 20 pinion 214 permitting their effect to be equalized. With both the tread-abutment and the fork thus bearing upon the work ready for the initiation of final pressure, and the force exerted through the treadle continuing, I have provided for relative movement of the slide 180 and the heel-engaging members 184 and 186. This is permitted by mounting the spindle 218 of the pinion 214 in vertical slots 220 in the slide. Fulcrumed at 221 upon the slide at the rear of the pinion is a

25 double lever 222, which is drawn down upon the pinion-spindle 218 by tension-springs 224, 224. At 226, the lever extends above the push-button of the switch 109. As long as only one of the abutments bears upon the heel, the spindle 218 30 remains at the lower extremity of the slots 220. When, however, both abutments engage said heel, the racks 210 and 216, and therefore the pinion 214 and its spindle, are held against any substantial movement, but the slide 180 continues to 35 descend under the influence of the treadle. This lowers the fulcrum 221 of the lever 222, while the forward portion of the lever is held against movement by the stationary spindle. The result of this is to depress the end 226 of the lever, turning it sufficiently clockwise (Fig. 2) to actuate the 40 switch-button. This closes the circuit through the solenoid 108, advancing the loop 112 so the 45 detents 98 are freed to be forced by their springs 102 into engagement with the teeth upon the nut 94. This locks the spindle 92 against movement, so the forward end of the lever 88, with the last-bed-piece 90 and the supported work, are held 50 against depression. This support of the last-cone divides the clamping pressure with the sleeve 55 22. At the end of the screw-inserting operation, when the treadle is released and the pressure-head P resumes its raised position, the lever 222 turns contraclockwise, freeing the button of the switch 109 to open the circuit of the solenoid.

60 The loop 112 is thereupon drawn back by the spring 114, removing the detents from the teeth of the nut. This releases the spindle 92, which is elevated by the spring 118, restoring the lever 88 and the last-bed-piece 90 to their normal 65 positions.

When the heels being operated upon are of the Cuban type, or others having comparatively straight backs, it is a common practice with compensating hold-downs, such as that herein illustrated, to lock the front rack-bar 210 to the slide 180 by inserting a pin 229 through aligned openings 230 in the side walls of the slide and in a depression 232 in the bar. The openings and depression are so related that with the pin in place, the tread-abutment is held down and the

rear fork raised clear of the heel, the entire clamping pressure being applied by the former. Obviously, when thus arranged, the depression of the hold-down would not turn the lever 222 to actuate the button of the switch 109. To provide for locking the lever 88 under such conditions, I vertically elongate the openings 230, the rack-depression 232 being as usual. There is thus a capacity for limited relative movement between the locking pin 229 and the slide. At 234 the lever 222 is extended forwardly and downwardly, so its end lies just above the locking pin 229, when this is inserted through the openings and depression. With the pin in place, the bottom of the elongated openings 230 will be initially in contact with said pin and the end 234 of the lever separated from it. When in the lowering of the pressure-head the tread-abutment is stopped by contact with the heel, movement of the openings in the further descent of the slide 180 is sufficient to carry the lever-end 232 against the pin. As before, the resulting clockwise oscillation of the lever is sufficient to cause the closing of the switch 109 and the energization of the solenoid 108 to lock the last-supporting lever 88.

The clutch C, through which the screw-driver 38 is elevated, is preferably tripped as an incident to the depression of the treadle-lever 130, it occurring just as the foot-pad 132 is approaching its lowest point, so substantially full clamping pressure is upon the work. At 146 there is pivoted to the treadle a rod 242 (Fig. 4), which at its upper extremity has threaded upon it an adjustable collar 244 (Figs. 2 and 7). The collar normally lies above and is spaced from a pin 246 projecting from one side of a lever 248 fixed to a fulcrum-spindle 250 rotatable transversely of the support 12. Depending from the rear of the lever 248 is a link 252, which, when lifted against the force of a spring within the clutch mechanism, frees said mechanism for a single rotation. The rod 242 passes through an opening in a plate 254 and in a link 256, to the upper edge of which the plate is attached. Said link extends horizontally from its pivotal connection to a depending arm 258 of the lever 248, it then being curved downwardly to a crank-pin 260 projecting from the end of the shaft 84, which is rotated to raise and lower the screw-driver 38. The rod is held normally at the rear of the plate-opening by a crossbar 262, movable in a depression 264 at the underside of the plate and drawn yieldably toward the front of the machine by tension-springs 266, 266 joining the crossbar to the plate.

When the operator treads, the rod 242 is drawn down and, as the foot-pad 132 approaches its lowest extreme of movement, the collar 244 is carried by the rod from the position indicated in full-lines in Fig. 7 to the dash-line position. The under surface of the collar striking the pin 246 tilts the lever 248. This lifts the link 252 sufficiently to trip the clutch C, starting the operation of the screw-driver 38. The link 252 must be released promptly to permit the disengagement of the clutch at the termination of the operating cycle. This is effected by the link 256. As the plunger 76 elevates the screw-driver, the rack 80 and pinion 82 turn the crank-pin 260 clockwise (Fig. 7). The forward edge of the opening through the link and its plate swings the rod 242 to the right, removing the collar 244 from above the pin 246. This releases the lever 248, so the link 252 is depressed to cause the

clutch to be disengaged and the screw-driver stopped in its normal position. When the lever 248 is freed from the collar and turns counter-clockwise, the periphery of the collar will rest against the pin. As the rotation of the crank-pin returns the link to its initial position, jamming of the collar against the pin is avoided by the yield of the bar 262 against the tension of the springs 266. When the operator releases the treadle, the rod 242 rises, the collar leaving the pin and resuming its normal position.

The work having been clamped and the clutch C engaged as just described, transmission of the screw-inserting force back to the treadle mechanism T is prevented by the following means. Referring to Figs. 1, 2, 5 and 6, each of the side-rods 122 has associated with it a clutch c' of the Horton type. Each side-rod passes through a cage at 270, in which a roll 272 is interposed between a fixed inclined surface 274 and a vertical wear-plate 276 upon the adjacent face of the side-rod. The roll is urged upwardly to produce the gripping effect by spring-plungers 278, 278, and may be depressed and normally retained by a plunger 280 bearing upon its upper side. Above the upper extremity of each plunger 280 extends an arm 282 fast upon a shaft 284 rotatable in the support 12. The shaft has secured upon it an intermediate arm 286, which lies below a cam-projection 288 from the forward face of the driver-actuating cam 74. In the normal position of this cam 274, the cam 288 is so located that it depresses the arm 286 and therefore both the arms 282, the latter bearing upon the plungers 280 and lowering the rolls 272. This releases the clutches c' and leaves the side-rods free for movement by the treadle mechanism. As soon as the power-cycle of the machine starts following the tripping of the clutch C, the cam-projection 288 leaves the arm 286. This, freeing the plunger 280 of each clutch c' from the arm 282, permits the plungers 278 to raise the roll into clutching engagement with its side-rod. The pressure-head is thus temporarily secured against retraction, regardless of the inserting force exerted upon the screw and without requiring effort on the part of the operator.

In the use of the machine of this invention, the operator places a screw s, head down, within the outer tube 22 upon the end of the tube 24, and spindles a lasted shoe S with the last-plate-shoulder 1 resting upon the end of the outer tube, locates a heel H upon the heel-seat and depresses the treadle 130. Through the chain of connections, including the link 147, the top-girt 124 carrying the pressure-head P is rapidly lowered. The slide 180, which has been held rearwardly by the collar 208 to give space for the positioning of the work upon the tube, is shifted forward by the spring 202 as it descends, effectively establishing contact of the tread-abutment 184, and then the rear abutment 186 with the heel. The crown of the last-cone has engaged the last-bed-piece 90 upon the auxiliary work-supporting lever 88 and lowered this, and, as the two abutment members are stopped in their descent by the heel, the floating pinion 214 transmits further downward movement of the slide 180 to the lever 222. The resulting oscillation of this lever closes the circuit of the solenoid 188 at the switch 109, to lock the nut 94 against rotation about the spindle 92, preventing further depression of the last-bed-piece. Pressure applied to the work will now be distributed between the last-plate and the last-cone. As depression of the treadle by the oper-

ator is continued, engagement of the clutch *c* transfers the action of the treadle to the head *P* through the link 170 with a much increased pressure determined by the loaded spring 172 to clamp the work firmly for the screw-inserting operation. As the foot-pad 132 of the treadle approaches its lowest point, the rod 242 actuates the lever 248 to trip the clutch *C*, thus initiating the power-cycle of the machine. In this cycle, the screw-supporting tube 24 and the screw-driver 38 are raised together by the cam 74, the tube yielding as the point of the screw contacts with the insole of the shoe and the travel of the screw-driver continuing. This establishes engagement between the clutch-plates 56 and 46, the spring 52 being compressed, and the screw-driver is rotated through the gearing 54, 58. The screw-driver-bit 40 enters the slot in the screw, with a slight pause in rotation while it seats itself, and then forces said screw into the work, the rate of rotation and axial movement corresponding to the pitch of the screw. Insertion continues until the screw-driver has been elevated to an extent, determined by the contour of the cam 74, at which the head of the screw is sunk in the insole, as appears in Fig. 10. After this, the screw-driver and tube 24 are lowered, the clutch-plates separate and the power-cycle terminates. Disengagement of the clutch *C* is permitted by the freeing of the clutch-controlling lever 248 from the treadle-rod 242 by the link 256, through the gearing 80, 82, as the screw-driver is elevated by the cam. By means of the hand-lever 86, this gearing may also be utilized to lift the screw-driver and the sleeve 24 for inspection and the removal of obstructions. Since the holding down of the work by the head *P* during the insertion of the screw is dependent upon the pressure of the operator's foot upon the treadle-pad, communication of reaction of the inserting pressure back to the operator's foot is prevented by locking the side-rods 122 by the clutch devices *c*, *c'*, against upward displacement. These clutch devices are rendered ineffective by the cam 288 until the action of the screw-driver begins, upon which they are freed to hold the side-rods and pressure-head independently of the treadle mechanism. Upon completion of the power-cycle, the operator releases the treadle, the head *P* rises, and the abutments 184 and 186 are withdrawn rearwardly from the work-support by the collar 208. In this movement, the abutments free the lever 222, so the switch 109 opens the circuit which has locked the auxiliary work-support 88, 90. The shoe with its attached heel may now be removed from the tube 22.

Having described my invention, what I claim as new and desire to secure by Letters Patent of the United States is:

1. In a fastening-inserting machine, a work-support, a screw-driver co-operating with the support, and means for rotating the screw-driver and for advancing it at a rate corresponding to the pitch of the attaching screw to be inserted in the supported work.

2. In a fastening-inserting machine, a work-support, a screw-driver co-operating with the support, means for rotating the screw-driver, and means for advancing said screw-driver through a predetermined distance, the rate of rotation and the rate of advance corresponding to the pitch of the attaching screw to be inserted in the supported work.

3. In a fastening-inserting machine, a work-

support, a screw-driver co-operating with the support, constantly rotatable driving means, automatically releasable means for connecting the screw-driver to the driving means, and means for advancing said screw-driver through a predetermined distance, the rate of rotation and the rate of advance corresponding to the pitch of the attaching screw to be inserted in the supported work.

10. 4. In a fastening-inserting machine, a work-support, a screw-driver co-operating with the support, means for rotating the screw-driver and for advancing it at a rate corresponding to the pitch of the attaching screw to be inserted in the supported work, and a friction-clutch interposed between the screw-driver and the rotating and advancing means.

5. In a fastening-inserting machine, a work-support, a screw-driver co-operating with the support, gearing by which the screw-driver is rotated at a predetermined rate, and a cam by which the screw-driver is advanced at a predetermined rate.

25. 6. In a fastening-inserting machine, a work-support, a screw-driver co-operating with the support, gearing by which the screw-driver is rotated at a predetermined rate, a friction-clutch having a section, rotatable by the gearing and a section connected to the screw-driver, and a cam by which the screw-driver is advanced at a predetermined rate.

35. 7. In a fastening-inserting machine, a work-support, a screw-driver co-operating with the support, gearing by which the screw-driver is rotated at a predetermined rate, and a cam by which the screw-driver is advanced at a predetermined rate and through a predetermined distance.

40. 8. In a fastening-inserting machine, a work-support, a screw-driver co-operating with the support, constantly rotatable driving means, means by which the screw-driver is rotated from the driving means at a predetermined rate, a cam movable to advance the screw-driver at a predetermined rate, means by which the cam is rotated from the driving means, and a single-rotation clutch included in the means for rotating the cam.

50. 9. In a heel-attaching machine, a shoe-support, a support associated with the shoe-support for the head of a screw, a screw-driver, means for rotating the screw-driver, means for forcing the bit of the screw-driver against the screw-head upon its support, and means for stopping the rotation of the screw-driver as the bit seats itself in the slot of the screw-head.

55. 10. In a heel-attaching machine, a shoe-support, a support associated with the shoe-support for the head of a screw, a screw-driver, constantly rotatable driving means, clutch members connected to the screw-driver and driving means respectively, a spring normally separating the clutch-sections, and means for urging the clutch member of the driving means against that of the screw-driver to force the screw-driver-bit against the head of a screw upon its support.

60. 11. The combination with a tube adapted to receive a passage in the cone of a last, of a tube situated within the first tube for engagement with the head of a screw, and a screw-driver movable in the screw-engaging tube.

65. 12. The combination with a tube adapted to support a lasted shoe, of a screw-supporting tube within the last-supporting tube, a screw-driver situated within the tubes, and means for rotating the screw-driver and advancing it through the

70. 75.

tubes at a rate corresponding to the pitch of the screw engaged.

13. The combination with a tube adapted to receive a passage in the cone of a last, the outside diameter of said tube being greater than that of the passage-opening through the heel-seat-portion of the last, of a tube situated within the first tube for engagement with the head of a screw, and a screw-driver movable in the screw-engaging tube.

14. The combination with a tube adapted to receive a passage in the cone of a last, of a tube situated within the first tube for engagement with the head of a screw, a screw-driver rotatable in the screw-engaging tube, and means for advancing the screw-engaging tube and the screw-driver together and for permitting the tube to remain at rest while the advance of the screw-driver continues.

15. The combination with a tube adapted to support a lasted shoe, of a screw-supporting tube movable within the last-supporting tube, means for moving the screw-supporting tube toward the work, means for yieldably retracting the screw-supporting tube, and a screw-driver movable within the screw-supporting tube.

16. The combination with a tube adapted to support a lasted shoe, of a screw-supporting tube movable within the last-supporting tube, means for moving the screw-supporting tube toward the work, means for yieldably retracting the screw-supporting tube, a screw-driver movable within the screw-supporting tube, and means for moving the screw-driver yieldably.

17. The combination with a tube adapted to support a lasted shoe, of a reciprocating screw-supporting tube within the last-supporting tube, a reciprocating screw-driver within the screw-supporting tube, means through which the screw-supporting tube and the screw-driver are advanced toward the work, a spring interposed between the screw-supporting tube and a relatively fixed point, and a spring interposed between the screw-driver and the advancing means.

18. The combination with a frame member, of a tube rising therefrom and adapted to receive a passage within the cone of a last, a screw-supporting tube movable within the last-receiving tube, a screw-driver movable within the screw-supporting tube, a driven clutch-section secured to the screw-driver and acting upon the screw-supporting tube, a driving clutch-section cooperating with the driven section and movable in the frame, and means for rotating and reciprocating the driving clutch-section.

19. The combination with a frame member, of a tube rising therefrom and adapted to receive a passage within the cone of a last, a screw-supporting tube movable within the last-receiving tube, a screw-driver movable within the screw-supporting tube, a driven clutch-section secured to the screw-driver and acting upon the screw-supporting tube, a driving clutch-section cooperating with the driven section and movable in the frame, means for rotating and reciprocating the driving clutch-section, and a spring movable with the driving clutch-section and by which the driven clutch-section is supported.

20. The combination with a frame member, of a tube rising therefrom and adapted to receive a passage within the cone of a last, a screw-supporting tube movable within the last-receiving tube, a screw-driver movable within the screw-supporting tube, a driven clutch-section secured

to the screw-driver and acting upon the screw-supporting tube, a driving clutch-section cooperating with the driven section and movable in the frame, means for rotating and reciprocating the driving clutch-section, a spring movable with the driving clutch-section and by which the driven clutch-section is supported, and springs interposed between the driven clutch-section and the screw-supporting tube and between the screw-supporting tube and the frame.

21. In a fastening-inserting machine, a rotatable cam, a plunger engaged by the cam, a clutch-section rotatable upon the plunger, gearing by which the clutch-section is rotated, a spring carried by the clutch-section, a second clutch-section resting upon the spring, a screw-driver secured to the second clutch-section, and a tube within which the screw-driver is movable.

22. In a fastening-inserting machine, a rotatable cam, a plunger engaged by the cam, a clutch-section rotatable upon the plunger, gearing by which the clutch-section is rotated, a spring carried by the clutch-section, a second clutch-section resting upon the spring, a screw-driver secured to the second clutch-section, and a tube within which the screw-driver is movable, and arranged to receive a passage in the cone of a last.

23. In a fastening-inserting machine, a rotatable cam, a plunger engaged by the cam, a clutch-section rotatable upon the plunger, gearing by which the clutch-section is rotated, a spring carried by the clutch-section, a second clutch-section resting upon the spring, a screw-driver secured to the second clutch-section, a screw-supporting tube surrounding the screw-driver and yieldable upon the second clutch-section, and a normally fixed tube surrounding the screw-supporting tube and adapted to receive a passage in the cone of a last.

24. In a fastening-inserting machine, a rotatable cam, a plunger engaged by the cam, a clutch-section rotatable upon the plunger, gearing by which the clutch-section is rotated, a spring carried by the clutch-section, a second clutch-section resting upon the spring, a screw-driver secured to the second clutch-section, a screw-supporting tube surrounding the screw-driver upon the second clutch-section, a spring acting to lower the screw-supporting tube, a spring permitting relative movement between the screw-supporting tube and the screw-driver, and a normally fixed tube surrounding the screw-supporting tube and adapted to receive a passage in the cone of a last.

25. In a heel-attaching machine, a frame, a nut threaded upon the frame, a tube supported by the nut and adapted to receive a passage in a last-cone, a screw-supporting tube movable in the last-receiving tube, and a screw-driver movable in the screw-supporting tube.

26. In a heel-attaching machine, a tube adapted to receive a passage in a last-cone, a screw-supporting tube reciprocable in the last-receiving tube, a screw-driver movable in the screw-supporting tube, means for elevating the screw-supporting tube under the power of the machine, and means arranged for actuation by the operator to elevate such tube.

27. In a fastening-inserting machine, a rotatable cam, a plunger engaged by the cam, a tube adapted to receive a passage in a last-cone, a screw-supporting tube reciprocable in the last-receiving tube, a screw-driver movable in the screw-supporting tube, said screw-driver and

screw-supporting tube being carried by the plunger, and means arranged for actuation by the operator to reciprocate the plunger.

28. In combination, a plurality of supports for a lasted shoe, one of said supports being movable by the work, means for applying pressure to the supported work, and means controlled by the pressure-applying means for locking the movable support.

29. In combination, a plurality of supports for a lasted shoe, one of said supports being movable by the work, means for applying pressure to the supported work, and means controlled by the pressure-applying means and including electromagnetic mechanism for locking the movable support.

30. In combination, a plurality of supports for a lasted shoe, one of said supports being movable by the work, means for applying preliminary and final pressure to the work, and means made effective upon the initiation of final pressure for locking the movable support.

31. In combination, a plurality of supports for a lasted shoe, one of said supports being movable by the work, mechanism through which pressure is applied to the supported work, said pressure-applying mechanism having relatively movable members, and means controlled by the relative movement of the members for locking the movable support.

32. In a heel-attaching machine, a plurality of supports for a shoe and heel, one of which supports is movable, means for locking the movable support, a pressure-head, two members relatively movable on the head for engagement with the heel, and means made effective upon the relative movement of the heel-engaging members for controlling the locking means.

33. In a heel-attaching machine, a plurality of supports for a shoe and heel, one of which supports is movable, means for locking the movable support, a pressure-head, two racks carried by the pressure-head, a heel-engaging member mounted upon each rack, a pinion connecting the racks, the pressure-head and pinion being relatively movable upon the application of pressure to the heel, and means made effective upon such relative movement for controlling the locking means.

34. In a heel-attaching machine, a plurality of supports for a shoe and heel, one of which supports is movable, means for locking the movable support, a pressure-head, two racks movable in the pressure-head, a heel-engaging member mounted upon each rack, a pinion connecting the racks for movement together and having a spindle, the pressure-head and spindle being relatively movable upon engagement of the members with the heel, a lever fulcrumed upon the head and contacting with the spindle, and means actuated by the lever for controlling the locking means.

35. In a heel-attaching machine, a plurality of supports for a shoe and heel, one of which supports is movable, means for locking the movable support, a pressure-head, two racks movable in the pressure-head, a heel-engaging member mounted upon each rack, a pinion connecting the racks for movement together and having a spindle, the pressure-head and spindle being relatively movable upon engagement of the members with the heel, a member co-operating with the pressure-head and with one of the racks to limit the relative movement, a lever fulcrumed upon the head and contacting with the move-

ment-limiting member, and means actuated by the lever for controlling the locking means.

36. In combination, a plurality of last-engaging members, one of which is movable, a screw and co-operating nut which are relatively movable and one of which furnishes a support for the movable last-engaging member, and means for producing the relative movement of the screw and nut and for locking them against such movement.

37. In combination, a spindle arranged to receive a passage in a last-cone, a relatively movable screw and nut, one of which is movable under the influence of the last, and means for locking the screw and nut against relative movement.

38. In combination, a spindle arranged to receive a passage in a last-cone, a relatively movable screw and nut, one of which is movable under the influence of the last, and co-operating teeth and a detent for locking the screw and nut against relative movement.

39. In combination, a plurality of supports for a lasted shoe, one of said supports being movable by the work, a screw movable by the movable support, a nut surrounding the screw and retained against bodily movement, said nut being provided with teeth, a detent for engagement with the teeth, and means for causing such engagement of the detent.

40. In combination, a plurality of supports for a lasted shoe, one of said supports being movable by the work, a screw movable by the movable support, a nut surrounding the screw and retained against bodily movement, said nut being provided with teeth, a detent for engagement with the teeth, and electromagnetic mechanism for causing such engagement of the detent.

41. In combination, a plurality of supports for a lasted shoe, one of said supports being movable by the work, means for applying pressure to the supported work, a contact device actuated by the pressure means, and electromagnetic mechanism controlled by the contact device for locking the movable support.

42. In combination, a support movable by contact with a last, a screw movable by the support, a nut rotatable by the screw and retained against bodily movement, and electromagnetic mechanism for locking the nut against rotation.

43. In combination, a support movable by contact with a last, a screw movable by the support, a nut rotatable by the screw and retained against bodily movement, said nut being provided with teeth, a detent for engagement with the teeth, a solenoid having a plunger controlling the position of the detent, and means for energizing the solenoid.

44. In combination, a support movable by contact with a last, mechanism for applying pressure to the lasted work, a screw movable by the support, a nut rotatable by the screw and retained against bodily movement, said nut being provided with teeth, a detent for engagement with the teeth, a solenoid having a plunger controlling the position of the detent, and means actuated by the pressure-applying mechanism for controlling the energization of the solenoid.

45. In a heel-attaching machine, a spindle for supporting a lasted shoe, a lever having means for engaging the crown of the last-cone, a screw connected to the lever, a nut engaging the screw and retained against bodily movement, said nut having teeth, a detent for engagement with the

teeth, and means for controlling such engagement.

46. In a heel-attaching machine, a spindle for supporting a lasted shoe, a lever having means for engaging the crown of the last-cone and depressible thereby, means for urging the engaging means along the spindle to receive such engagement, a screw connected to the lever, a nut engaging the screw and retained against bodily movement, said nut having teeth, a detent for engagement with the teeth, and means for controlling such engagement.

47. In a fastening-inserting machine, a frame, a work-support mounted thereon, a pressure-head movable toward and from the support, a treadle-lever fulcrumed upon the frame, a second lever fulcrumed upon the frame and connected to the pressure-head, clutch mechanism carried by the treadle-lever, clutch-levers fulcrumed upon the treadle-lever, a link connecting the second lever and the clutch-levers, and a link connected to the second lever and arranged for engagement by the clutch mechanism.

48. In a fastening-inserting machine, a frame, a work-support mounted thereon, a pressure-head movable toward and from the support, a treadle-lever fulcrumed upon the frame, a second lever fulcrumed upon the frame and connected to the pressure-head, clutch mechanism carried by the treadle-lever, clutch-levers fulcrumed upon the treadle-lever, a link connecting the second lever and the clutch-levers, and a link connected to the second lever and arranged for engagement by the clutch mechanism, the leverage upon the pressure-head produced by the clutch-engaged link through the second lever being greater than that of the link joining said second lever to the clutch-levers.

49. In a fastening-inserting machine, a frame, a work-support mounted thereon, a pressure-head movable toward and from the support, a treadle-lever fulcrumed upon the frame, a second lever fulcrumed upon the frame and connected to the pressure-head, clutch mechanism carried by the treadle-lever, clutch-levers fulcrumed upon the treadle-lever, a link connecting the second lever and the clutch-levers, a link connected to the second lever and arranged for engagement by the clutch mechanism, the leverage upon the pressure-head produced by the clutch-engaged link through the second lever being greater than that of the link joining said second lever to the clutch-levers, and a spring included in the clutch-engaged link.

50. In a fastening-inserting machine, a work-support, a pressure-head movable toward and from the support, a heel-engaging member movable upon the head, a lever connected to the heel-engaging member, and a member fixed relatively to the lever and into and out of active engagement with which said lever moves.

51. In a fastening-inserting machine, a frame, a work-support mounted upon the frame, a pressure-head movable upon the frame toward and from the support, a slide movable upon the head, a lever fulcrumed upon the head and connected to the slide, and a rod attached to the frame and provided with means into and out of engagement with which the lever moves in the travel of the head.

52. In a fastening-inserting machine, a frame, a work-support mounted upon the frame, a pressure-head movable upon the frame toward and from the support, a slide movable upon the head, a bell-crank-lever fulcrumed upon the head, a

link connecting the lever to the slide, a spring joining the lever to the head, and a rod attached to the frame and having fixed to it a collar into engagement with which the lever moves in the travel of the head.

53. In a fastening-inserting machine, a work-support, a movable tool for operating upon the supported work, a clutch through which the tool is moved, a lever, a clutch-controlling member carried by the lever, a treadle, a rod movable by the treadle into engagement with the lever to actuate the clutch-controlling member, and means acting upon the rod to release the lever therefrom.

15 54. In a fastening-inserting machine, a work-support, a reciprocable tool for operation upon the supported work, a member by which the tool is reciprocated, a clutch through which the member is reciprocated, a lever, a clutch-controlling member carried by the lever, a treadle, a rod movable by the treadle into engagement with the lever to actuate the clutch-controlling member, and means movable by the tool-reciprocating member in engagement with the rod to release the lever therefrom.

25 55. In a fastening-inserting machine, a work-support, a movable tool for operating upon the supported work, a clutch through which the tool is moved, a lever, a clutch-controlling member carried by the lever, a treadle, a rod movable by the treadle into engagement with the lever to actuate the clutch-controlling member, and means having a yieldable portion engaging the rod to release the lever therefrom.

35 56. In a fastening-inserting machine, a work-support, a reciprocable tool for operating upon the supported work, a plunger by which the tool is reciprocated, a shaft geared to the plunger and having a crankpin, a clutch through which the plunger is reciprocated, a lever, a clutch-controlling member carried by the lever, a treadle, a rod movable by the treadle into engagement with the lever to actuate the clutch-controlling member, and a link connected to the crankpin and acting upon the rod to release the lever therefrom.

45 57. In a fastening-inserting machine, a work-support, a reciprocable tool for operating upon the supported work, a plunger by which the tool is reciprocated, a shaft geared to the plunger and having a crankpin, a clutch through which the plunger is reciprocated, a lever, a clutch-controlling member carried by the lever, a treadle, a rod movable by the treadle into engagement with the lever to actuate the clutch-controlling member, a link connected to the crankpin, and a member yieldable upon the link for engaging the rod.

55 58. In a fastening-inserting machine, a frame, a work-support mounted upon the frame, a movable tool co-operating with the support, a movable pressure-head co-operating with the support, a rod guided in the frame and through which the pressure-head is actuated, the rod and frame having opposite relatively inclined surfaces, a clutch member for engagement with the surfaces, retaining means by which the member is held normally out of clutching engagement with the surfaces, and means acting upon movement of the tool for releasing the clutch member from the retaining means.

60 59. In a fastening-inserting machine, a frame, a work-support mounted upon the frame, a movable tool co-operating with the support, a movable pressure-head co-operating with the sup-

port, a rod guided in the frame and through which the pressure-head is actuated, the rod and frame having opposite relatively inclined surfaces, a clutch member, a spring by which the clutch member is urged into clutching engagement with the surfaces, a member movable to overcome the force of the spring, and means acting upon movement of the tool to actuate said member.

60. In a fastening-inserting machine, a frame, a work-support mounted upon the frame, a movable tool co-operating with the support, a movable pressure-head co-operating with the support, a rod guided in the frame and through which the pressure-head is actuated, a cage through which the rod passes, said cage and rod having opposite relatively inclined surfaces, a roll contained in the cage between said surfaces, a spring by which the roll is urged against the surfaces, a power-shaft, a cam upon the shaft by which the tool is moved, a second cam upon the power-shaft, a second shaft, an arm upon the second shaft for engagement by the

second cam, and an arm upon the second shaft acting to overcome the force of the spring.

61. In a fastening-inserting machine, a frame, a work-support mounted upon the frame, a movable tool co-operating with the support, opposite side-rods guided upon the frame, a pressure-head carried by the side-rods and co-operating with the support, clutch devices carried by the frame for engagement with both side-rods, and means for controlling both clutch devices.

62. In a fastening-inserting machine, a frame, a work-support mounted upon the frame, a movable tool co-operating with the support, opposite side-rods guided upon the frame, a pressure-head carried by the side-rods and co-operating with the support, clutch devices carried by the frame for engagement with both side-rods, a power-shaft having a cam by which the tool is moved and a second cam, and a shaft provided with arms controlling both clutch devices and with an arm engaged by the second cam.

FRANK E. STRATTON.
